VIBRATOR TESTING APPARATUS

Harold V. Elliott and Brooks H. Short, Anderson,
Ind., assignors to General Motors Corporation,
Detroit, Mich., a corporation of Delaware

Original application May 15, 1948, Serial No.
27,237. Divided and this application July 18,
1949, Serial No. 109,198

2 Claims. (Cl. 175—183)

1

This invention relates to apparatus for converting direct current from low voltage to higher voltage and more particularly to the vibrator which distributes current in succession to the primary windings of a transformer.

An object of this invention is to provide apparatus which will give a visual indication of the functioning of the vibrator to determine whether its contacts have been properly adjusted to obtain the required contact separation.

A vibrator which is adapted to be tested by the present apparatus is described and claimed in copending application, Serial No. 27,237, filed May 15, 1948, of which this application is a division, now Patent No. 2,541,223 issued February 13, 1951.

Further objects and advantages of the present invention will be apparent from the following description, reference being had to the accompanying drawings wherein a preferred embodiment of the present invention is clearly shown.

In the drawings:

Fig. 1 is an enlarged scale longitudinal sectional view of a vibrator which is adapted to be tested by the present apparatus.

Fig. 2 is a sectional view on line 2—2 of Fig. 1.

Fig. 3 is a reduced scale view of the tool which is used in adjusting the vibrator contacts.

Fig. 4 is a wiring diagram showing the connections of the vibrator with a current source and primary windings of a transformer.

Fig. 5 is a wiring diagram of the apparatus for determining whether the contacts have been properly adjusted.

Referring to Figs. 1 and 2 the vibrator comprises a frame 20 which provides a magnetic circuit including a core 21 and pole pieces 22. The core 21 extends through a spool which comprises parts 23 and 24 of molded insulating material upon which are wound a tape layer 25a, a coil 25 of wire and a tape layer 25b. An insulating spacer 26 and the assembly of spool and coil are placed upon the core 21 while the pole pieces 22 are spread apart. After making this assembly the parts 22 are bent into parallelism as shown in Fig. 2. One end of the coil 25 marked 27 in Fig. 1 is attached to the frame 20 and the other end is connected to a lead wire 28. The corners of core 21 are deformed to retain the

screws 30 secure to the frame 20 a stack of parts comprising an insulator 31, metal contact springs 32l and 33l in the same plane carrying respectively contacts 34l and 35l (Figs. 4 and 5),

2

metal contact spring supports 36 in the same plane, an insulator 31, a metal spacer plate 38, a terminal plate 39, a reed 40, a second terminal plate 39, a second spacer plate 38, a second insulator 31, metal contact spring supports 36 in the same plane, metal contact springs 32r and 33r in the same plane and supporting, respectively, contacts 34r and 35r (Figs. 4 and 5), an insulator 31, a metal plate 41. All parts of said stack parts are insulated from the screws 30 by nonconducting sleeves 42 except the plate 41. Lock washers confined between the heads of the screws 30 and the plate 41 resist accidental loosening of the screws. The four insulators 31, the two spacers 38, the plate 41, the two terminals 39 and the reed 40 each have two holes receiving the bushings 42. The contact springs and the contact spring supports each have one hole for receiving a bushing. The grain of the metal of the reed is in the direction of the longer dimension of the reed.

The contacts 34l, 35l, 34r, 35r are engageable respectively with movable contacts 54l, 55l, 54r, 55r each having a spherical face and welded to a rivet 50. Rivets carrying contacts 54l and 55l are attached to resilient contact supports 57l; and the rivets carrying contacts 54r and 55r are attached to resilient contact supports 57r. Supports 57l and 57r are attached by rivets 58 to the reed 40. An armature 60 is attached to the reed 40 by rivets 61 passing through the armature, the reed and a plate 62 against which the rivets are upset.

A wire 70 connects frame 20 with terminal plates 39 and reed 40 and plates 39 are connected by wire 71 with terminal 72 (Fig. 4). Wire 28 (Fig. 4) is connected with blade 33r which carries contact 35r and this blade is connected by wire 73 with a terminal 74. The blade 32r which carries contact 34r is connected by wire 75 with terminal 76. The blade 32l which carries contact 34l is connected by wire 77 with a terminal 78. The blade 33l which carries contact 35l is connected by wire 79 with a terminal 80.

The vibrator is connected as shown in Fig. 4 with the current source and primary windings of a transformer. Terminal 72 is connected by wire 90 and switch 91 with a storage battery 92 having one terminal grounded. The terminals 74, 76, 78 and 80 are connected respectively with transformer primary sections 94, 96, 98 and 100 which are grounded at 101. The transformer secondary 102 is connected with a rectifier, the output terminal of which is connected with the apparatus,

such as a high frequency ignition system, requiring for its operation relatively high voltage direct current. Satisfactory operation of the vibrator is obtained provided the contact closing periods of all of the vibrator contacts are such that energization of the four sections of the primary of the transformer are equalized. In order to determine whether such equalization exists the vibrator is tested by the apparatus shown in Fig. 5 and its relatively fixed contacts are adjusted during the test in order to obtain equalization.

The test apparatus comprises a lever 110 which operates a shaft 111 carrying switch arms 112, 113, 114, 115, 116 and 117 which are connected respectively with vibrator side contacts 34l, 35l, the vibrator coil 25, contacts 35r and 34r and ground. The other end of coil 25 is grounded and the reed supported contacts are grounded. Switch arm 112 is engageable with contacts 121, 122, 123, 124, arm 113 with contacts 131, 132, 133, 134, arm 114 with contacts 141, 142, 143, 144, arm 115 with contacts 151, 152, 153 and 154, arm 116 with contacts 161, 162, 163 and 164 and arm 117 with contacts 171, 172, 173 and 174. Contacts 121, 124, 132 and 133 are connected by wire 180 with transformer primary section 181. Contact 134 is connected by wire 182 with transformer primary section 183. Wire 184 connects contacts 141, 142, 143, 144, 153, 154, 161, 162 with transformer primary section 185. Wire 186 connects contact 164 with transformer primary section 187. The primary sections are connected with a battery 188 which is grounded. The transformer secondary wiring 190 is connected as shown with a buffer condenser 191, rectifier tubes 192 and 193, resistances 194, 195 and voltage doubling condensers 196 and 197 connected respectively with rectifier output terminals 198 and 199, the former being grounded and the latter being connected with loading resistances 200 and 201. A cathode ray oscilloscope 210 is connected between wires 180 and 184 in such a manner as to detect the behavior of the primary sections 181 and 185 and will show on a screen the traces of wave forms in these primary sections. The traces A indicate the behavior of one of the sections and the traces B the other. C is the base line on the screen. If the slanting portions a are equal in length to the slanting portions b, this is an indication that the energization of the transformer primary sections are equal, because the slant portions represent the functioning of the buffer condenser 191. If two primary sections 181 and 185 are equally energized the buffer condenser will be equally discharged at the time the opposite pairs of contacts are closed.

For convenient reference in the description which follows the four pairs of cooperating vibrator contacts are marked I, II, III, IV. To begin the test the switch handle 110 is moved from an off-position into the first position shown in Fig. 5 thereby connecting contact pairs I and III respectively with primary sections 185 and 181. If the wave forms on the oscilloscope screen are not equal, an adjustment of contacts 34l or 34r is made by bending the contact spring supporting plates 36 against which the contact supporting spring are biased. It will be observed that each plate 36 has a relatively narrow neck 36n, the bending of which will displace the head 36h of the plate 36 so as to change the normal contact gap. The bending of the neck 36n is effected by the T-shaped tool 220 shown in Fig. 3

which includes a handle integral with a shank 221 having a notch 222 wide enough to easily receive the neck 36n. By turning the handle the plate 36 can be easily bent in order to change the location of the fixed contact of a pair relative to the movable contact. The spacing of contact pairs I and III is adjusted by means of the tool until the wave form shows equal lengths of slants a and b as shown in Fig. 5. In the second operative position of the switch handle 110, contacts III are dropped out and contacts I and IV are connected respectively with the primary sections 185 and 181. The side contact 35l is adjusted so that contacts IV are balanced with contacts I. Contacts III and IV are now balanced with contacts I and can be used for duplex operation. The third operating position of the switch handle 110 drops contacts I, retains contacts IV connected with primary section 181 and connects contact II with primary section 185. Contacts II are balanced with contacts IV by adjusting the supports 36 which controls the position of contact 35r. All four sets of contacts are now balanced and the vibrator is presumably properly adjusted. In the fourth position of the switch all four sets of contacts are connected respectively with the transformer primary sections for full load operation and both resistances 200 and 201 are connected between the rectifier terminals 199 and 198. If the wave forms shown on the oscilloscope screen compares favorably with the wave forms obtained in the other three positions of the switch, the adjustment of the vibrator is satisfactory. If the wave forms obtained in the fourth position of the switch shows inequality, the test is repeated and further contact adjustments are made. Generally one repetition of the test is all that is required to perfect the adjustment of the contacts.

While the embodiment of the present invention as herein disclosed, constitutes a preferred form, it is to be understood that other forms might be adopted, all coming within the scope of the claims which follows.

What is claimed is as follows:

1. Apparatus for testing a vibrator having a reed fixed at one end, an armature supported by the other end of the reed, an electromagnet having a core offset from the armature and a coil surrounding the core, and first, second, third and fourth pairs of contacts, each pair including a reed-supported contact and a fixed contact normally separated from the reed-supported contact, the fixed contacts of the first and second pairs being at same side of the reed as the magnet core and the fixed contacts of the third and fourth pairs being on the opposite side of the reed, a transformer having its primary winding provided by four primary coils and having a secondary winding, a buffer condenser and a rectifier connected with the secondary winding, a loading resistance connected with the rectifier, a current source having one terminal connected with one end of each of the primary coils and the other terminal connected with the reed and with one end of the magnet coil, a cathode ray oscilloscope connected with the other end each of a certain two of the primary coils, switches having movable contacts respectively connected with the fixed contacts of the four pairs of vibrator contacts and a movable contact connected with that end of the magnet coil remote from the end connected with the current source, a manually operable member for moving the movable contacts simultaneously into different posi-

tions, circuits established by one of the movable contacts in each of its positions for completing a circuit between the magnet coil and one of said two primary coils whereby the magnet coil is energized to cause the reed to swing in the direction of the fixed contacts of the first and second pairs of vibrator contacts, circuits established by two of the other movable switch contacts in the first position of the member for connecting the fixed contacts of the first and third pairs of vibrator contacts respectively with those ends of said one of, and of the other one of said two primary coils remote from the ends connected with the current source, the closing of the first pair of vibrator contacts short-circuiting the magnet coil so that the reed swings away from the magnet core and effects opening of the short circuit and engagement of the third pair of reed contacts, circuits established by another two of the movable switch contacts in the second position of the member for connecting the fixed contacts of the first and fourth pairs of vibrator contacts respectively with those ends of said one of, and of the other one of said two primary coils remote from the ends connected with the current source, the closing of the first pair of vibrator short-circuiting the magnet coil so that the reed swings away from the magnet core and effects opening of the short circuit and engagement of the fourth pair of reed contacts, and circuits established by another two of the movable switch contacts in the third position of the member for connecting the fixed contacts of the second and fourth pairs of vibrator contacts respectively with those ends of said one of, and of the other one of said two primary coils remote from the ends connected with the current source,

the closing of the second pair of vibrator contacts short-circuiting the magnet coil so that the reed swings away from the magnet core and effects opening of the short-circuit and engagement of the fourth pair of vibrator contacts.

2. Apparatus according to claim 1 in which, in the fourth position of the manually operable member, circuits are established by said four switch movable contacts which are respectively connected with fixed contacts of the four pairs of vibrator contacts for respectively connecting said fixed vibrator contacts with ends of the four primary coils remote from those ends connected with the current source and which, in the fourth position of the manually operable member, there is another switch actuated by movement of the member for connecting another loading resistance with the rectifier output terminals.
